UNITED STATES PATENT OFFICE.

FRED A. CONRAD, OF MILWAUKEE, WISCONSIN, ASSIGNOR TO AMERICAN LACE PAPER COMPANY, OF MILWAUKEE, WISCONSIN, A CORPORATION OF WISCONSIN.

DESIGN FOR A PAPER DOILY.

Application filed October 22, 1928. Serial No. 28,595. Term of patent 14 years.

To all whom it may concern:

Be it known that I, FRED A. CONRAD, a citizen of the United States, residing at Milwaukee, in the county of Milwaukee and State of Wisconsin, have invented a new, original, and ornamental Design for Paper Doilies, of which the following is a specification, reference being had to the accompanying drawing, forming part thereof.

The drawing shows the design applied to one third of a doily, the remaining individual

third portions thereof being identical respectively to the part shown.

There are fine intersecting ribs, as shown at 2, in the central portion 1 of the doily. The areas 3 and 5 are plain. The areas 6 and 7 are in a higher plane than areas 3 and 5.

I claim:

The ornamental design for a paper doily substantially as shown and described.

FRED A. CONRAD.
